UNITED STATES PATENT OFFICE.

HENRY KOCH, OF NYACK, NEW YORK.

TEST-INDICATOR.

No. 825,911.

Specification of Letters Patent.

Patented July 17, 1906.

Application filed May 4, 1906. Serial No. 315,184.

To all whom it may concern:

Be it known that I, HENRY KOCH, a citizen of the United States, and a resident of Nyack, in the county of Rockland and State of New York, have made and invented certain new and useful Improvements in Test-Indicators, of which the following is a specification.

My invention relates to an improvement in test-indicators—that is, an indicator used to test and determine the imperfections of inside, outside, or surface work, and also employed for testing lathe-centers or work held between centers and for setting centrally a hole or point in a piece of work under operation in a lathe or upon a face-plate—the object being to provide a device of this character which shall be simple and economical in construction, accurate in its operation, and so constructed and arranged as to avoid any liability of getting out of order.

With these and other ends in view the invention consists in certain novel features of construction and combinations of parts, as will be hereinafter fully described, and pointed out in the claims.

In the accompanying drawings, Figure 1 is a perspective view of a test-indicator constructed in accordance with my invention. Fig. 2 is a plan view of the same with the cover removed. Fig. 3 is a similar view showing the parts in an indicating position. Fig. 4 is a sectional view taken on the line 4 4 of Fig. 3. Fig. 5 is a sectional view taken on the line 5 5 of Fig. 3. Fig. 6 is a sectional view taken on the line 6 6 of Fig. 2.

By reference to the drawings it will be seen that the operative parts of the indicator are contained within a metal box or receptacle A, having a removable cover B extending nearly the length of the box, but leaving a lateral opening C between the end of said cover B and the graduated gage-plate D, screwed or otherwise secured to the forward end of the box A, and through which opening may be seen the end of the indicating-lever E.

The forward end of the box A is provided with the tube or barrel F, through which extends the rod G, the opposite end of the latter resting in the sleeve H, set in the rear end of the box A. The forward end of the rod G is provided with the rounded end or knob I, adapted to come into contact with the surface of the article under test, and also with the disk J, adapted to limit the movement of the

rod G by striking against the end of the barrel F.

Encircling the rod G is the spiral spring K, one end of which impinges against the shoulder formed by the enlargement k and the opposite end against the inner end of the sleeve H, the tendency of the spring being to force said rod G outwardly, as illustrated in Fig. 2, so that the end of the indicating needle or lever E will normally rest at zero on the graduated plate D.

To the forward end of the box is pivoted at l the bell-crank lever L, the short arm m of which is bifurcated, as illustrated in Figs. 4 and 6, and straddles the rod G, somewhat reduced in diameter, as shown at n, forming two shoulders n' and n'', whereby when said rod G is forced toward the forward end by the spring K said shoulder n', striking the short arm m, will swing the longer arm L to 85 its normal position—that is, toward one side of the box A, as indicated in Fig. 2—the bifurcation of the arm m at the same time allowing the rod G to be freely pushed backwardly by pressure on the forward end I without positive engagement of said rod with said arm m.

To the rear end of the box or receptacle A is pivoted at o the bent lever or indicating-needle E, from the under side of which projects downwardly the pin e, against which latter bears the free end of the lever L and on the opposite side of which pin e bears the free end of the spring M, the opposite end of said spring being secured in the forward end of the receptacle A, the tendency of said spring M being to force the free end of the indicating lever or needle E toward the fulcrum of the bell-crank lever L. As the tendency, however, of the spring K is somewhat greater than that of the spring M, the lever or needle E is held in its normal position, as indicated in Fig. 2.

When pressure is applied to the end I of the rod G by some imperfection in the article under test, the rod G is forced backwardly, overcoming the tension of the spring K, whereupon the tension of the spring M, bearing on the pin e, will immediately move the free end of the indicating needle or lever E toward the opposite end of the graduated plate D. When, however, the pressure on the end I of the rod G is relieved, the spring K will force the rod G forwardly, whereby the shoulder n'', striking the shorter arm m of the bell-crank lever, will move said arm for- 120

ward and the end of the longer arm L, bearing against the pin e on the lever E, will move said indicating needle back to its normal position, as indicated in Fig. 2. In other words, 5 when the rod G is moved backwardly by pressure on the end I, the indicating-needle E will be moved toward the opposite end of the graduated plate D, as illustrated in Fig. 3, and when the pressure is relieved on said rod 10 the spring K, overcoming the tension of the spring M, will move the indicating-needle back into its normal position, as indicated in Fig. 2.

From the foregoing it will be understood 15 that instead of one lever acting directly upon the indicating-needle to move the same, as is usually the case in indicators as now commonly constructed, I simply overcome by pressure the tension of one spring, whereby to 20 allow the latter spring to move or operate the indicating-needle, and thereby avoid any and all danger of disrupting, breaking, or disarranging the parts when a sudden jar or blow 25 is given to the rod or lever employed to engage and move the indicating-lever.

As it is sometimes required to employ the indicator in a narrow constricted space or opening between the parts of an article under test, I secure in the back of the case A the 30 sleeve H, provided with the slotted rod N, in which is fulcrumed at r a bell-crank lever, the longer arm O of which rests in and projects out beyond the slotted rod N, as clearly indicated in Figs. 1, 2, and 3, the end of the 35 short arm P of which lever fits in a groove or recess s in the rear end of the rod G. By reason of this construction and arrangement of parts it will be understood that when the end of the arm O is forced inwardly the short 40 arm P will force backwardly the rod G, overcoming the tension of the spring K and operating in every way the same as though pressure were applied to the forward end of the rod I and resulting in moving the indicating 45 lever or needle E, as illustrated in Fig. 3. In such instances, therefore, where the contracted space between the parts will not permit of applying the forward end I of the rod to the work the post or rod N may be inserted, 50 bringing the end of the arm O into contact with the work and by movement of which arm O the imperfections in said work will be indicated by the lever E. The under side of the box A may have formed thereon 55 or secured thereto the threaded post S, whereby to secure the indicator to a handle or other device (not shown) of any desired shape or pattern.

Having fully described my invention, what 60 I claim as new, and desire to secure by Letters Patent, is—

1. An indicator of the character described, comprising a casing, a spring-actuated rod extending through the same, an indicating-

needle, a lever engaging with needle at one 65 end and said rod at the other end, and a spring engaging said needle for moving the same, substantially as described.

2. An indicator of the character described, comprising a casing, a rod extending through 70 the same, a spring for holding said rod in its normal position, an indicating-needle pivoted to said casing, a spring secured to said casing and engaging said needle for moving the latter in one direction, and a lever pivoted to 75 said casing and engaging said needle and said rod for moving said indicating-needle in the opposite direction, substantially as described.

3. An indicator of the character described, comprising a casing, a rod extending longitudinally through the same, a spring for holding said rod in its normal position, an indicating-needle pivoted at one end of said casing, the opposite end being free, a spring secured 80 at one end, and at its opposite end engaging 85 said needle for moving the latter in one direction, and a bell-crank lever, one arm of which engages said needle, and the other arm of which engages said rod for moving said needle in the opposite direction, substantially 90 as described.

4. An indicator of the character described, comprising a casing, a rod extending longitudinally through said casing, a spring for holding said rod in its normal position, an indicating-needle pivoted at one end to said casing, its opposite end being free, and provided with a pin, a spring secured to said casing and engaging the pin on said needle for moving the latter in one direction, a bell-crank 100 lever pivoted to said casing, one arm of which engages said pin on said needle, and the other arm of which straddles and engages said rod, whereby to move the needle in the opposite direction, substantially as described. 105

5. A test-indicator of the character described, comprising a casing, a rod extending longitudinally through the same, a spring for holding said rod in its normal position, an indicating-needle pivoted at one end to said casing, its opposite end being free, and provided with a pin, a spring secured at one end to said casing, the opposite free end engaging said pin, a bell-crank lever pivoted to said casing, one arm of which engages said rod, 115 the other arm engaging said pin, and a bell-crank lever pivoted in said casing, one arm of which extends outwardly therefrom, and the other arm of which engages the rear end of said rod, substantially as described. 120

Signed at Nyack, in the county of Rockland and State of New York, this 2d day of May, A. D. 1906.
